UNITED STATES PATENT OFFICE.

SAMUEL H. GIBSON, OF CLEVELAND, OHIO, ASSIGNOR TO THE FANNER MFG. CO., OF CLEVELAND, OHIO, A CORPORATION OF OHIO.

METAL-BENDING MACHINE.

Application filed June 16, 1922. Serial No. 568,779.

This invention relates to a machine for bending metal strips into desired shapes. More particularly the machine is intended to make chaplets and for this purpose embodies a machine which receives a strip of metal, severs the same when a proper length has been fed into the machine and has instrumentalities which further operate to bend the strip of metal around a forming die and discharge the product from the forming die after the article is completely formed.

The present invention is an improvement over my Patent No. 1,348,215, granted Aug. 15, 1920.

Objects of the present invention are to simplify the construction of the cam operated slides which carry actuating and forming members whereby they are made more readily removable for replacement or repair and also to provide a more efficient and more easily accessible spring suspension for the slides.

A further object is to provide connections between the slides which are more readily accessible for adjustment or removal of the tools.

A further object is to provide adjustable mountings for the shaping and actuating members upon the bed and upon the slides and tools whereby a single machine may be used to make chaplets of different sizes.

Generally speaking, the invention may be said to comprise the elements and combinations thereof set forth in the accompanying claims.

In the annexed drawing forming a part of this specification, Figure 1 is a side elevation of the machine; Fig. 2 is a top plan view of the machine; Fig. 3 is a partial side elevation of the machine, the elevation being taken from the side opposite that shown in Fig. 1; Fig. 4 is a front elevation of the machine; Fig. 5 is a top plan view of the bed plate and parts mounted thereon; Figs. 6 and 7 are edge and side views respectively of the slide plate carrying the actuating members for the transversely movable formers mounted on the bed plate; Fig. 8 is a side elevation of the slide plate upon which the cutter is mounted; Figs. 9 and 10 are edge and side views respectively of a portion of the plate upon which the bridge

former is mounted; Figs. 11, 12 and 13 are sectional views showing the different positions of the forming members in operating upon a metal strip to form a chaplet; and Fig. 14 is a perspective view of a finished chaplet.

Referring to the annexed drawings, the supporting frame 1 has a forwardly projecting base plate 2 upon which is removably supported a bed plate 3 adapted to support a stationary die and certain forming members associated therewith. The bed plate 3 has a dovetail groove 4 extending transversely thereacross in which is slidably mounted a forming die 5 having a recess 6 in its upper face, a supporting block 7 on one side of the die which carries a stop member 8 which projects inwardly from the block toward the die and on the opposite side of the die 5, a feed platform 9 supported by springs 9^a upon a platform supporting block 10 slidably in the groove 4. To the inner face of the block 10 is secured a cutter bar 11 which has its upper edge substantially even with the top of the platform 9 in the normal position of the platform. The die 5, stop 8 and the block 10 carrying the platform and cutter bar are all adjustably and removably secured within the groove 4 of the bed plate so that the die 5 may be replaced by larger or smaller dies and the stop 8 and cutter bar 11 may be adjusted to cut blanks of different lengths. The die 5 and blocks 7 and 10 are held in adjusted position by means of set screws 5^a, 7^a and 10^a respectively. At the upper edges of the die 5 on the sides thereof toward the stop 8 and cutter bar 11 are a pair of transversely movable former members 12 and 13 which are carried by slide blocks 14 mounted in a groove 15 beside the die receiving groove 4 and parallel therewith. A coil spring 16 is interposed between the blocks 14 and set screws 17 engaging the outer ends of the blocks 14 serve to adjust the blocks to properly position the former members 12 and 13 with respect to the die 5. The blocks 14 carry upwardly projecting inclined shoulder lugs 19 which are adapted to cooperate with vertically movable actuating members to move the blocks 14 inwardly in opposition to the spring 16 to move the forming members 12 and 13 to-

ward each other across the upper face of the die 5. When the blocks 14 are in their normal position in engagement with the set screws 17, the former members 12 and 13 are positioned at the side edges of the die 5 and form a continuation of the recess 6 in the die so that the strip of metal to be formed is adapted to be fed over the die and to be supported in place over the die 10 to be engaged by the movable die and forced into the recess 6 in the die 5.

Mounted in the housing 20 in the frame 1 above the base plate 2 is a horizontal drive shaft 21 which carries at its forward end a 15 series of narrow cams 22 side by side thereon. Beneath the drive shaft 21 and over the bed plate 3 is a rectangular housing 23 in which a series of slide plates are placed side by side in engagement with each other for 20 vertical movement toward and from the bed plate 3. As shown herein, there are five slide plates designated respectively; 24; 25; 26; 27 and 28. Each of the slide plates carries a roller 29 upon its upper edge which 25 engages one of the cams 22 upon the drive shaft 21. Adjacent one edge thereof each slide plate has attached thereto a suspension rod 30, the upper end of which is attached to the lower end of a coil spring 31, the upper end of which is attached to a suspension rod 32 supported from a bracket 33 secured to the top of the shaft housing 20. By suspending the slide plates from springs outside 30 the housing 23 it is possible to place the 35 plates in the housing with their side faces in contact and to easily remove individual plates from the housing.

The plate 24 is provided adjacent its lower edge with a dovetail rib 34 projecting from the outer face thereof. Adjustably secured to the rib 34 are a pair of former actuating blocks 35 which are provided at their lower ends with inclined shoulders 36 adapted to engage with the inclined shoulders 19 upon the former supporting blocks 14. The blocks 35 have a rabbeted upper edge and are clamped to the rib 34 by means of a rabbeted attaching block 37 which is secured to the block 35 and clamped upon the rib 34 by means of clamping bolts 38. By loosening clamping bolts 38 the blocks 35 may be adjusted along the rib 34 and set screws 39 adjacent opposite ends of the rib 34 serve to accurately position the actuating blocks 35.

Detachably secured to the lower edge of the slide plate 25 is a forming die 40 which has a laterally extending foot piece 41 which engages in the recess 6 in the stationary die 5. As shown in Fig. 11 the movable former members 12 and 13 are actuated to bend the strip of metal over the top of the foot piece 41 while the foot piece is in the recess 6 of the stationary die.

66 Detachably mounted on the lower edge of

the slide plate 26 is a shaper die 42 which engages the sheet metal flaps turned over the top of the foot piece 41 and forces them into conformity with the upper surface of the foot piece.

A bridge flange former and presser block 43 is detachably and adjustably secured to a dovetail 44 formed on the lower edge of the slide plate 27. The presser block 43 is secured to the dovetail 44 by means of an attaching block 45 and clamping bolts 46. An adjusting screw 47 at the end of the dovetail 44 is engageable with the presser block 43 and serves to accurately position the block. The presser block 43 engages the spring supported platform 9 immediately behind the cutter bar 11 and cooperates with the rear face of the cutter bar 11 to form a short bridge flange upon the end of a strip which has been severed by the cutter bars.

A cutter supporting block 48 is adjustably connected upon an external rib 49 formed on the side of the slide plate 28 adjacent its lower edge. The block 48 is secured in adjusted position by means of clamping bolts 50. A cutter plate 51 is secured by bolts 52 to the lower end of the adjustable block 48 and projects inwardly therefrom over the cutter bar 11. By means of the adjustable connection of the block 48 with the slide plate 28 the cutter plate 51 can be adjusted to correspond to the adjustment of the cutter bar 11 on the bed plate 3. The cams 22 are arranged to actuate the slide plates in proper sequence.

To eject the finished article from the foot piece 41 an ejector collar 53 is slidably mounted thereon. The collar 53 is normally at the inner end of the foot piece 41 so that it is clear of the die 5 during the forming operation. The collar 53 is connected by an arm 54 with a crank arm 55 carried by a vertical shaft 56 journaled in the frame 1. The shaft 56 has an upper crank arm 57 in which is a longitudinal slot 58 having a block 59 slidably mounted therein and adjustable therealong by a screw 60. A link 61 connects the block 59 with a slide plate 62 mounted in a guideway 63 in the shaft housing 20. A grooved cam 64 is carried by the shaft 21 to the inner side of the cams 22, and the slide 62 has a pin 65 engaging in the peripheral groove of the cam 64. The cam groove has an offset 66 which serves to actuate the slide plate 62 which through the link 61 imparts a turning movement to the vertical shaft 56 and actuates the ejector collar 53 through the crank arm 55. By adjusting the block 59 in the slot 58 the extent of angular movement of the shaft 56 and consequently the extent of movement of the ejector collar 53 may be varied. This adjustment is useful since it permits the ejector to be used with forming dies of different widths. The offset 66 in the cam groove is so positioned that the 130

ejector is actuated after all the forming operations have been completed and the foot piece 41 has been raised from the die 5.

In operation a strip of metal is fed inwardly across the platform 9 into engagement with the stop 8. The slide plate 28 is actuated to move the cutter plate 51 over the inner upper edge of the cutter bar 11 to sever the strip. The slide plate 27 carrying the presser block 43 follows slightly behind the slide plate 28 causing the block 43 to press the platform 9 down and to coact with the rear face of the cutter bar 11 to form a flange 67 at the forward end of the severed strip. The slide plate 25 is then actuated to lower the forming die 40, forcing the blank into the recess 6 of the die 5 as shown in Fig. 11. The slide plate 24 is next actuated to cause the formers 12 and 13 to move inwardly toward each other over the upper face of the foot piece 41 of the forming die 40 as shown in Fig. 12. The slide plate 26 is next actuated to bring the shaper die 42 down upon the metal folded over the foot piece 41 as shown in Fig. 13. The foot piece 41 of the die 40 has a slot 41¹ to receive the flange 67 at the forward end of the strip as it is bent over the foot piece 41 by the forming member 12. The height of the flange 67 is substantially equal to the thickness of the foot piece 41 so that in the finished chaplet as shown in Figs. 13 and 14, the flange 67 forms the bridge of the chaplet. On return of the movable die 40 to its raised position the ejector collar 53 is actuated to eject the chaplet.

By reason of the adjustable connections above described, the die members may be removed and replaced by die members adapted to form larger or smaller chaplets and the adjustable cutting and forming members can be correspondingly adjusted to provide a blank of proper size and to cooperate with the dies in shaping such articles.

Having described my invention, I claim:

1. In a machine of the character described, the combination with a stationary bed having a stationary die, and movable forming members mounted thereon, of a drive shaft having a series of cams thereon above said bed, a series of slide plates arranged side by side in contact with each other and housed for vertical movement above said stationary bed, each of said plates having a part in engagement with a cam on said shaft, a spring suspension for each of said plates mounted above the plates and connected to the upper ends thereof for holding the plates in engagement with the cams, forming members secured to the lower ends of certain of said plates, and actuating members for the movable members on the stationary bed carried upon the lower ends of other of said plates.

2. In a machine of the character described,

the combination with a stationary bed having a stationary die and movable forming members mounted thereon, of a drive shaft having plates housed for vertical movement above said bed, cams on said shaft each of said plates having a part engaging with one of said cams, a fixed support above said shaft, suspension springs connecting each of said plates with said support to hold said plates in engagement with said cams, forming members secured to the lower ends of certain of said plates, and actuating members for the movable members on said stationary bed carried upon the lower ends of other of said plates.

3. In a machine of the character described, the combination with a stationary bed having a stationary sheet metal forming die and a stop member and a cutter member on opposite sides thereof mounted for adjustment toward and from said die, of vertically movable cutter and forming members cooperating with said cutter member and die upon said stationary bed, said movable cutter member being mounted for adjustments corresponding to the adjustments of the cutter member on the bed, said die and movable former being detachably mounted whereby they may be replaced with corresponding parts of a larger or smaller size.

4. In a machine of the character described, the combination with a stationary bed having a stationary sheet metal forming die, a stop member and a cutter member on opposite sides thereof mounted for adjustment toward and from said die and forming members mounted for movement transversely above said die and for bodily lateral adjustment with respect thereto, of vertically movable independently actuated slides, above said bed, a cutting member mounted upon one of said slides and adjustable thereon to register with cutter members on the bed in each of its adjusted positions, actuating members mounted on one of said slides and engageable with said transversely movable forming members, said actuating members being mounted for adjustments corresponding to the lateral adjustments of said forming members, and a forming member on another of said slides cooperating with said stationary die.

5. In a machine of the character described and in combination, a stationary bed, a die having a recess formed therein mounted upon said bed, a vertically movable forming die cooperating with said bed die, oppositely disposed movable members normally located above and at the sides of the recess in the bed die, the front faces of said movable members forming continuations of the sides of the recess in the bed die and serving as parts of said die during the initial bending of a strip of metal, and means for operating said movable members to reciprocate them across

the recess in the bed die thereby to fold the strip of metal about the forming die, said dies being detachably mounted whereby they may be replaced by larger or smaller dies, 5 and said movable members and the actuating means therefor being adjustably mounted whereby said movable members can be so adjusted that in normal position they form continuations of a larger or smaller die and 10 whereby the extent of movement of said movable members can be correspondingly varied.

6. In a machine of the class described, the combination with cooperating stationary and 15 movable dies, of cutters adjustably mounted with respect to said dies to vary the size of the blank operated upon, and auxiliary transversely movable forming members co-operating with said dies, said stationary and 20 movable dies being detachably mounted whereby they can be replaced with larger or smaller dies, and said auxiliary formers

being adjustable bodily toward and from the axis of said dies to coact with larger or smaller dies. 25

7. In a machine of the character described, the combination with a stationary bed having a stationary die, and movable forming members mounted thereon, of a drive shaft having a series of cams thereon above said bed, a series of slide plates housed for vertical movement above said stationary bed, each of said plates having a part in engagement with a cam on said shaft, and forming and actuating members secured to the lower 30 edges of said plates cooperating with the stationary and movable forming members on said bed, each of said members having a slidable connection with the lower edge of a plate, and means for clamping the same in 35 adjusted position thereon.

In testimony whereof, I hereunto affix my signature.

SAMUEL H. GIBSON.
